ANIMAL FEEDER

Furman E. Ott, Rte. 3, Laurens, S.C. 29360

Filed Mar. 13, 1967, Ser. No. 6,185

Term of patent 14 years

(Cl. D30—13)

Fig. 1.

Fig. 2.

I claim:

The ornamental design for an animal feeder, substantially as shown.
